CLAIM

The ornamental design for a food preportioning bag, as shown and described.

DESCRIPTION

FIG. 1 is a perspective view of a food preportioning bag showing my new design;

FIG. 2 is a front view thereof;

FIG. 3 is a side view thereof;

FIG. 4 is a bottom view thereof;

FIG. 5 is a back view thereof;

FIG. 6 is another side view thereof; and,

FIG. 7 is a top view thereof.

The broken lines shown in the drawings are for illustrative purposes only and form no part of the claimed design.
